COIL WINDER

Joseph M. Drees, Sunnyvale, and Kenneth L. Jones, Pacific Palisades, Calif., assignors to Sylvania Electric Products Inc., a corporation of Massachusetts

Application December 20, 1956, Serial No. 629,608

8 Claims. (Cl. 242—9)

This invention relates to coil winding apparatus, and more particularly is concerned with apparatus for winding very fine wire into coils or helices having an extremely precise spacing between turns.

In certain applications, for example in the fabrication of traveling wave tubes, it is necessary to employ coils or helices formed of extremely small wire, and for proper operation of the tube, it is essential that the spacing between turns be uniform to a high degree. It has been found, for example, that helices wound on gear-driven lathes, while apparently having uniform spacing between turns when examined by available precision gauging methods, did not provide satisfactory operation of the traveling wave tubes into which they were incorporated. The inoperativeness of the tube was due to the slight variation in the spacing between turns, imperceptible by the usual standards, caused it is believed, by the repetitive errors caused by the cyclic positioning of the gear teeth which are translated to the winding carriage.

It is an object of the present invention to provide apparatus for winding coils or helices having a precise and uniform turn-to-turn spacing.

Another object of the invention is to provide apparatus for winding coils or helices from wire of very small diameter and having uniform spacing between turns.

Another object of the invention is to provide apparatus of the class indicated in which the spacing between turns of the coil or helix is readily and conveniently adjustable.

Another object of the present invention is to provide apparatus for winding fragile coils or helices wherein the spacing between turns may vary in accordance with a predetermined function from one end of the coil to the other.

Still another object of the invention is to provide apparatus for winding multifilar coils or helices having a precise spacing between the turns of each coil and between the turns of one coil and the corresponding turn of the adjacent coil.

In the attainment of the foregoing objects, the apparatus contemplated by this invention employs a lathe for supporting and driving a coil winding mandrel in rotation, and on which a winding carriage is slidably mounted for movement parallel to the mandrel at a rate proportional to the angular velocity of the mandrel. The angular rotation of the mandrel is translated to a functionally related translational movement of the winding carriage through a system including a differential pulley and a series of wires or cables, thereby entirely eliminating the use of gears in the attainment of a suitable correlation between the angular velocity of the mandrel and the speed of travel of the winding carriage. Through the use of circular pulleys of different relative diameters, the pitch of coils having uniform turn-to-turn spacing can be readily changed, and should it be desired to have the spacing between turns vary from one end of the helix to the other in accordance with a predetermined function, a cam-shaped pulley of the proper contour to generate the function may be employed. The apparatus may also

2

include a dividing head affixed to the arbor which drives the winding mandrel to permit the winding of multifilar coils with uniform spacing between turns of each coil and between corresponding turns of adjacent coils.

5 Other objects, features and advantages of the invention will be apparent, and a better understanding of the construction and operation of a preferred form of the apparatus will be had from the following detailed description taken in connection with the accompanying drawings, in 10 which:

Fig. 1 is a front elevation view of a typical coil winder constructed in accordance with the invention;

Fig. 2 is a top plan view of the coil winder of Fig. 1;

Fig. 3 is an elevation cross-sectional view taken along line 3—3 of Fig. 2;

Fig. 4 is an elevation view, partially in section, taken along line 4—4 of Fig. 1;

Fig. 5 is an elevation view, partially in section, taken along line 5—5 of Fig. 1; and

20 Fig. 6 is an elevation view taken along line 6—6 of Fig. 5.

Referring to the drawings, and more particularly to Figs. 1 and 2, the coil winding apparatus of the invention is preferably mounted on a structure similar to a lathe, 25 having a suitably supported horizontally disposed bed 8 which, in turn, supports a horizontal plate 10. The plate 10 supports a bearing-support 16 at one end thereof, a bearing 34 for a precision spindle near the middle, and a somewhat conventional lathe tailstock at the other end.

30 A lead screw 12, rotatably journaled at one end on support 16, is coupled at the other end, for example, by coupler 14, to one end of a spindle journaled in bearing 34, on the other end of which is secured a chuck 30. The lead screw 12, and consequently chuck 30, are driven in

35 rotation by suitable driving means, such as an electric motor 24 supported on bed 8 and coupled to the lead screw by belt 20 passing over pulleys 18 and 22 respectively secured to an extension of the lead screw and the shaft of the motor. The helix or coil is wound on a 40 mandrel 26, a small diameter rod, held at one end by chuck 30 and rotatable therewith, and supported at the other end by a chuck 28 freely rotatable on the tailstock. Thus, it is seen that motor 24 drives the lead screw 12, chuck 30 and mandrel 26 in rotation at the same angular 45 velocity, about co-linear axes, there being no gears between the source of driving power and the mandrel. An indexing head 32 is provided on chuck 30 and is arranged to rotate the chuck in discreet angular steps with respect to the lead screw 12 to permit the convenient winding of multifilar coils, as will be more fully explained hereinafter. The motor 24 is controlled by a motor-controller 36, conveniently positioned near the mandrel 26, the electrical connections between the controller and motor being entirely conventional and omitted from the 50 drawing in the interest of clarity.

55 The rotational movement of lead screw 12 is converted to rectilinear motion of a carriage 38 which includes a lead screw nut 42 threaded on the screw 12 and constrained from rotation. In addition to the support afforded carriage 38 by the lead screw 12, it is slidably supported on bars 40 and 80, the ends of which are rigidly mounted on support 16 and the vertical supporting column for motor-controller 36. Thus, upon rotation of lead screw 12, carriage 38 is smoothly driven along bars

60 40 and 80 at a rate depending upon the angular velocity of the screw and in a direction depending upon the direction of rotation.

65 Referring to Figs. 3 and 4, lead screw nut 42 is threaded on lead screw 12 and is secured to carriage 38 through pivot members 94 and 96 to permit adjustment of the alignment between the axis of the lead screw and the direction of movement of the carriage. The carriage

is provided with bearings, shown generally at 98, to insure smooth travel over the carefully machined bar 40. Lead screw 12 and supporting bar 40 lie in the same vertical plane in the disclosed embodiment, and to provide greater stability and smoother operation, lead screw nut 42 is further supported and guided on bar 80, which lies in substantially the same horizontal plane with lead screw 12, and is supported at its ends with its longitudinal axis parallel to lead screw 12. Rigidly secured to the carriage 38 by threaded stud 81, and projecting toward the front of the lathe bed (as viewed in Fig. 2) is a quick-disconnect clamping member 82 adapted to receive and clamp the carriage to a cable or wire 50, the significance of which will appear hereinafter.

To summarize the description thus far, motor 24 drives lead screw 12 in rotation, which in turn, through the action of lead screw nut 42, imparts translational movement to carriage 38 which is a linear function of the angular velocity of lead screw 12. Motor 24 also drives chuck 30, and hence mandrel 26, at the same angular velocity as the lead screw. Thus, there remains to describe the wire-feeding carriage and means for imparting the translational movement of carriage 38 to the wire feeding carriage so as to lay the wire from the feeding carriage onto the mandrel with the desired spacing between turns.

Referring again to Figs. 1 and 2, and to Figs. 5 and 6 for details, winding carriage 44 is mounted on a horizontally disposed rod 46 for free movement therealong, the rod 46 being disposed parallel to the axis of mandrel 26 and rigidly supported at its opposite ends on the support for spindle 34 and on the tailstock of the lathe, respectively. Carriage 44 is additionally supported on a bearing 45, which travels on horizontal plate 16. A bobbin 86 of wire 87 of the type from which the coil or helix is to be wound is mounted on the carriage 44 for rotation about an axis parallel to mandrel 26, the wire 87 being fed from the bobbin over a wire guide 88, formed of nylon, for example, and positioned as nearly as practicable to mandrel 26, to ensure that the wire is always laid on the mandrel from the same position relative to the carriage 44. As shown in Fig. 5, a stud 83 secured to the carriage and extending toward the front of the lathe, supports a quick-disconnect clamp 84 for receiving and engaging a wire 72. Translational movement of carriage 44 is controlled only by the movement of the cable 72 along its length the driving action of which will now be described.

The heart of the driving means for imparting translational movement to the wire feeding carriage 44 as a predetermined function of the translational movement of lead screw carriage 38 is a differential pulley 48 mounted on lathe bed 10 for free rotation about a horizontal axis which is oriented at right angles to the lead screw 12 and mandrel 26. Pulley 48 is of a generally conical shape with a plurality of grooves of different diameter formed on the conical surface to provide, in effect, a plurality of coaxial pulleys of different diameters rotatable as a unit about a common axis. Alternatively, the pulley 48 may comprise a plurality of circular plates of different diameter, each formed with a peripheral groove, stacked in order of decreasing diameter and secured together as a unit. A series of wires or cables 50, 60 and 72 passing over the pulley 48, with cables 50 and 72 connected to the lead screw carriage 38, and wire feeding carriage 44, respectively, impart a translational movement to carriage 44 which is proportional to the movement of carriage 38, the movement of carriage 44 for each revolution of mandrel 26 being dependent upon the relative diameters of the pulleys over which the cables pass.

In more detail, cable 50, which may be a single strand of wire of high tensile strength, or preferably a flexible multiple-strand cable (the type used in aircraft is admirably satisfactory), is secured at one end to an anchor 58 projecting from pulley 48 near its outer periphery, passes over a selected groove of pulley 48, thence over

idler pulleys 56 and 54, a counterweight 52 being suspended from the other end. The position of idler pulleys 54 and 56 and the clamp 82 are adjustable to permit their being positioned in the same vertical plane as the selected groove of pulley 48 whereby carriage 38 may be attached to cable 50 without introducing transverse strains in the cable in the flight between pulleys 54 and 56 and to insure a uniform velocity ratio between lead screw carriage 38 and carriage 44. Clamp 82 is of the quick-release type, and is designed firmly to engage the cable 50 thereby to drive the cable upon movement of carriage 38 under the influence of lead screw 12.

A second cable 60, of the type similar to cable 50, is secured at one end to an anchor 70 in the outer peripheral groove of pulley 48, passes over a portion of the circumference of the pulley, passes over idler pulley 68, and is anchored to horizontal plate 10 at 62, a weight 66 being supported on pulley 64 in the loop in the cable between anchor 62 and pulley 68.

One end of the third cable 72 is also anchored to pulley 48 at 58, is wrapped around a selected groove of pulley 48, passes under idler pulley 78, which is mounted on the lathe bed for free rotation about a horizontal axis, is wrapped around a second idler pulley 76, with a weight 74 suspended from the other free end. Pulleys 76 and 78, and quick release clamp 84 are adjustable in a direction transversely of the lathe bed in order that they may be positioned in the same vertical plane with the selected groove of pulley 48 over which cable 72 passes. Clamp 84 is designed to engage cable 72 whereby carriage 44 is moved longitudinally along rod 46 in response to travel of cable 72 along its length.

With the cables 50, 60 and 72 laid on pulley 48 as illustrated, clockwise rotation of lead screw 12 (as viewed from the right end in Fig. 1) drives lead screw carriage 38 from right to left whereby cable 50 tends to turn pulley 48 in a counter-clockwise direction (as viewed from the front). This rotation of pulley 48, in turn, tends to wind cable 72 around the groove over which it passes, causing wire feeding carriage 44 to move from right to left and causes cable 60 to wind about pulley 48. It will be apparent that by reversing the direction of application of either of cables 50 or 72 to pulley 48 the carriage 44 will travel in a direction opposite from the direction of travel of the lead screw carriage, and if both are reversed from that shown, carriages 38 and 44 will again travel in the same direction.

It will be noted that carriage 38 is urged from right to left by counterweight 52 to minimize friction between lead screw 12 and nut 42 and to provide the torque necessary for the rotation of pulley 48. Counterweight 74 is necessary to maintain cable 72 taut to ensure faithful correlation between the rotation of pulley 48 and longitudinal movement of cable 72, and weight 66 is provided to permit convenient counterbalancing of the entire system and provide such tension as to obtain essentially frictionless movement of carriage 38, pulley 48 and carriage 44.

In preparing for the winding of a coil or helix, cables 50 and 72 are placed in selected grooves in pulley 48 (the selection being based on knowledge of the pitch of lead screw 12 and the proportionality introduced by the difference in diameters of the pulleys) to cause winding carriage 44 to move at a rate relative to the speed of rotation of mandrel 26 to lay on the desired number of turns per inch. With the cables placed in the selected grooves, weights 52, 66 and 74 are adjusted to balance the torque on pulley 48 to the extent that there is just sufficient unbalance to cause winding carriage 44 to return to its starting position (to the right in Fig. 1 with the illustrated configuration of cables) and to maintain all cables in tension. With carriages 38 and 44 at their starting positions, the free end of wire 87 is withdrawn from bobbin 86, is threaded over wire guide 88 and is attached to mandrel 26, for example, with a suitable adhesive.

Upon starting motor 24, rotation of lead screw 12 drives carriage 38 from right to left, which in turn, through the action of cable 50, causes pulley 48 to rotate in a counter-clockwise direction. This rotation of pulley 48 causes cable 72 to be wound onto the groove over which it passes causing wire-feeding carriage 44 to also move from right to left at a rate proportional to the speed of travel of carriage 38. With mandrel 26 being driven in rotation by chuck 30, the longitudinal movement of carriage 44 operates to lay a coil of wire onto mandrel 26 to form a helix having a predetermined pitch, or spacing between turns. There being no gears between carriage 38 and carriage 44, the correlation between their movements is extremely accurate and variations in spacing between turns of the helix which might be caused by cyclical errors in gear trains are entirely eliminated. It has been found that coils may be wound on the described apparatus from wire having a diameter of the order of .0005 inch with a spacing between turns of as little as .0015 inch to a very high degree of accuracy, much superior than was heretofore attainable. When the carriage 44 has traversed the length of mandrel 26 a distance corresponding to the desired length of the coil, the motor is stopped, the final turn of the coil is secured to the mandrel with an adhesive such as glue, cement, or the like, to prevent unwinding, the wire is cut, and the mandrel, with the coil thereon, is removed from the chuck 30 for further processing of the coil.

It will be apparent that so long as the peripheral grooves of pulley 48 over which cables 50, 60 and 72 pass are circular, the translational movement of carriage 44 will be in accordance with a linear function of the movement of carriage 38, and a uniform predetermined spacing between turns of the helix will result. Should a different spacing be desired, it is necessary only to select a different combination of pulleys to vary the linear function. In some applications, however, it may be desirable that the spacing between turns of the helix gradually vary from one end of the coil to the other in accordance with some function; e. g., very close spacing between turns at one end and a gradual increase in spacing toward the other end. Insofar as applicants are aware, a coil with these characteristics cannot be wound with suitable accuracy on existing coil winding machinery. With the present apparatus, such coils may be wound by merely replacing one of the circular pulleys of pulley 48, ordinarily the one over which cable 72 passes, with a cam-shaped pulley having a contour describing the desired function. With this modification, carriage 44 does not follow carriage 38 as a linear function, but instead, in accordance with a non-linear function determined by the shape of the cam, thereby introducing the desired variation in spacing between the turns of the coil, the mandrel 26, as before, being driven at the same uniform angular velocity as the lead screw.

The disclosed apparatus also conveniently lends itself to the winding of multifilar windings. After winding a single coil of uniform spacing between turns, or of varying spacing between turns, as just described, a second coil of like spacing but spaced slightly from the first, may be laid on the mandrel by turning dividing head 32 through a sub-multiple of a turn, for example a quarter turn, and repeating the winding process. In this connection, the machine has been found capable of winding a multifilar winding of 20 separate coils of .0005 inch diameter wire, with a spacing between corresponding turns of adjacent coils of .0015 inch with a high degree of accuracy.

Although the invention has been shown and described in terms of a specific preferred embodiment, applicants are aware that many modifications thereof are possible. The invention, therefore, is not to be restricted except insofar as is necessitated by the spirit of the following claims.

What is claimed is:

1. Winding apparatus for winding wire on a mandrel to form a coil or helix with a predetermined spacing between

turns comprising, in combination, a lathe including a lead screw and a chuck for holding said mandrel, means for driving said lead screw and said chuck in rotation, a lead screw nut threaded on said lead screw arranged for longitudinal movement therealong in response to rotation of said screw, a wire-feeding carriage arranged for longitudinal movement along a path adjacent and parallel to the rotational axis of the mandrel, and means including a differential pulley and first and second cables passing over said pulley and respectively connected to said lead screw nut and to said carriage arranged to drive said carriage in response to and as a predetermined function of the movement of said lead screw nut.

2. Winding apparatus for winding wire on a mandrel to form a coil or helix with a predetermined spacing between turns comprising, in combination, a lathe including a lead screw and a chuck for holding said mandrel, means for driving said lead screw and said chuck in rotation about co-linear axes, a lead screw nut threaded on said lead screw arranged for longitudinal movement therealong in response to rotation of said screw, a wire-feeding carriage arranged for longitudinal movement along a path adjacent and parallel to the rotational axis of the mandrel, and means including a pulley having a plurality of peripheral grooves of different contours and first and second cables passing over selected ones of said grooves and respectively connected to said lead screw nut and to said carriage arranged to drive said carriage in response to and as a predetermined function of the movement of said lead screw nut.

3. Winding apparatus for winding wire on a mandrel to form a coil or helix with a predetermined spacing between turns comprising, in combination, a lathe including a lead screw and a chuck for holding said mandrel, means for driving said lead screw and said chuck in rotation at the same angular velocity about co-linear axes, a lead screw nut threaded on said lead screw arranged for longitudinal movement therealong in response to rotation of said screw, a wire-feeding carriage arranged for longitudinal movement along a path adjacent and parallel to the rotational axis of the mandrel, a pulley having a plurality of peripheral grooves of different contours arranged for free rotation about an axis perpendicular to the axis of said lead screw, first and second cables passing over selected ones of said grooves and respectively connected to said lead screw nut and to said carriage arranged to drive said carriage in response to and as a predetermined function of the movement of said lead screw nut, and means connected to said cables for maintaining said cables in tension.

4. Coil winding apparatus for winding wire on a mandrel comprising, in combination, a rotatable chuck for holding said mandrel, a lead screw rotatable with said chuck, means for driving said lead screw and said chuck in rotation, a first carriage mounted on said lead screw and arranged for longitudinal movement therealong in response to rotation of said screw, a second carriage arranged for longitudinal movement along a path adjacent and parallel to the mandrel when held in said chuck, said second carriage including means for feeding wire onto said mandrel, a pulley having a plurality of peripheral grooves of different contours mounted for free rotation about an axis perpendicular to the axis of said lead screw, and a pair of cables respectively connected to said first and second carriages and each passing over one of said grooves for driving said second carriage at a predetermined rate relative to the rate of travel of said first carriage.

5. Coil winding apparatus for winding wire on a mandrel comprising, in combination, a lathe including a lead screw and a chuck for holding said mandrel, means for driving said lead screw and said chuck in rotation about co-linear axes at the same angular velocity, a first carriage including a lead screw nut mounted on said lead

screw, and arranged for longitudinal movement therealong in response to rotation of said screw, a second carriage arranged for movement along a path adjacent and parallel to said mandrel when held by said chuck and including means for feeding wire onto said mandrel from a direction substantially normal to the axis of said mandrel, a pulley having a plurality of peripheral grooves of different contours freely rotatable about an axis perpendicular to the axis of said lead screw, a pair of cables respectively connected to said first and second carriages and each passing over one of said grooves for driving said second carriage at a predetermined rate relative to the rate of travel of said first carriage.

6. Coil winding apparatus for winding wire on a mandrel comprising, in combination, a lathe including a lead screw and a chuck rotatable with said lead screw for holding said mandrel, means for driving said lead screw and said chuck in rotation, a lead screw nut threaded on said lead screw and movable therealong in response to rotation of said screw at a rate determined by the pitch and angular velocity of said screw, a wire-feeding carriage arranged for movement along a path adjacent and parallel to the mandrel when held by said chuck including a bobbin of wire and means for laying wire onto said mandrel from a direction substantially normal to the axis thereof, a pulley having a plurality of peripheral grooves and freely rotatable about an axis perpendicular to the axis of said lead screw, a first cable anchored at one end to said pulley and passing over a selected one of said grooves and attached to said lead screw nut, a second cable also anchored at one end to said pulley and passing over a selected other one of said grooves and attached to said wire-feeding carriage, said pulley and said cables being arranged to drive said wire-feeding carriage along said path in response to movement of said lead screw nut along said screw as a predetermined function of the movement of said lead screw nut.

7. Coil winding apparatus for winding wire on a mandrel comprising, in combination, a lathe including a

lead screw and a chuck rotatable with said lead screw for holding said mandrel, means for driving said lead screw and said chuck in rotation about co-linear axes, a lead screw nut threaded on said lead screw and movable therealong in response to rotation of said screw at a rate determined by the pitch and angular velocity of said screw, a wire-feeding carriage arranged for movement along a path adjacent and parallel to the mandrel when held by said chuck and including a bobbin of wire and means for laying wire onto said mandrel from a direction substantially normal to the axis thereof, a pulley having a plurality of peripheral grooves arranged to be freely rotatable about an axis perpendicular to the axis of said lead screw, a first cable guided by means on said lathe with a flight thereof substantially parallel to the axis of said lead screw and passing over a selected one of said grooves and anchored at one end to said pulley, means secured to the other end of said first cable for maintaining said first cable in tension, means securing said lead screw nut to said flight of said first cable, a second cable guided by means on said lathe with a flight thereof lying along said path and passing over a selected other one of said grooves and anchored at one end to said pulley, means secured to the other end of said second cable for maintaining said second cable in tension, and means securing said wire-feeding carriage to said flight of said second cable, said wire-feeding carriage being driven by said second cable in response to and as a predetermined function of the movement of said lead screw nut.

8. Apparatus in accordance with claim 4 and means including a third cable anchored at one end to said pulley for controlling the relative tensions in said first and second cables.
